UNITED STATES PATENT OFFICE.

SAMUEL H. BAKER, OF PASADENA, AND CARRIE S. FORD, OF SANTA MONICA, CALIFORNIA.

DESIGN FOR A LAMP.

48,514.

Specification for Design.

Patented Feb. 8, 1916.

Application filed December 4, 1915. Serial No. 65,146. Term of patent 14 years.

To all whom it may concern:

Be it known that we, SAMUEL H. BAKER and CARRIE S. FORD, citizens of the United States, residing at Pasadena, Los Angeles county, California, and Santa Monica, Los Angeles county, California, respectively, have invented a new, original, and ornamental Design for Lamps, illustrated in the accompanying drawing, in which—

We claim:—

The ornamental design for a lamp, as shown.

SAMUEL H. BAKER.
